CLAIM

The ornamental design for an earbud charging case, as shown and described.

DESCRIPTION

The present application is related to U.S. Design patent application Ser. No. 29/611,494, entitled Wireless Earbud Arrangement, filed concurrently herewith, the entire disclosure of which is incorporated herein by reference.

FIG. 1 is a front perspective view of an earbud charging case according to our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a front perspective view of an earbud charging case according to our design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top elevation view thereof; and,

FIG. 14 is a bottom elevation view thereof.

The broken lines shown in the drawings are included for the purpose of illustrating environmental structure and form no part of the claimed design.
